UNITED STATES PATENT OFFICE

JOHN CHARLES COTTAM, OF BRADFORD, AND JOSEPH BENTLEY, OF SHIPLEY, ENGLAND.

STOP-MOTION FOR LOOMS.

SPECIFICATION forming part of Letters Patent No. 657,691, dated September 11, 1900.

Application filed May 18, 1900. Serial No. 17,134. (No model.)

To all whom it may concern:

Be it known that we, JOHN CHARLES COTTAM, residing at Bradford, and JOSEPH BENTLEY, residing at Shipley, in the county of York, 5 England, have invented certain new and useful Improvements in the Construction of Stop-Motions for Looms, (for which we have applied for provisional protection in Great Britain, No. 19,507, dated September 28, 1899,) of 10 which the following is a specification.

This invention has for its object certain improvements whereby the friction on the shuttle between the fixed flange at the front of the shuttle-box and the "swell" at the back or 15 opposite side of the shuttle-box is reduced at the time when the shuttle is in the position to be driven from one shuttle-box to another, and thereby to proportionately reduce the wear and tear of the cams, picking-sticks, 20 straps, and pickers of the loom utilized for operating the shuttle.

In describing our invention in detail, reference is made to the accompanying sheets of drawings, in which—

25 Figure 1 represents the front elevation of such portions of a weaving-loom as are required to explain our invention, which is more particularly shown in the detached details, hereinafter explained. Those parts of 30 the loom not required for explaining our invention are of the ordinary and well-known construction and are omitted from the drawings. Fig. 2 represents the end elevation of a loom with the stop-fingers held clear of the 35 stop-blocks. Fig. 3 is a section through the loom on line *a b* of Fig. 1, with the stop-rod fingers in contact with the stop-blocks. The remainder of the figures are detached details drawn to an enlarged scale. Fig. 4 is a de- 40 tailed detail view showing the application of a plate or flat spring for forcing the stop-rod fingers into the position shown. Fig. 5 is an end view of the lay-beam, with the stop-rod fingers held clear of the stop-blocks; Fig. 45 6, a back view of one end of the lay-beam; Fig. 7, a plan of one end of the lay-beam, and Fig. 8 a section through the stop-rod shaft with hooked arm and a portion of the spiral spring on the opposite side of the stop-rod 50 shaft to that of the stop-rod fingers. Fig. 9 is an end view of the stop-rod shaft with the

hooked arm and a portion of the spiral spring on the same side of the shaft as the stop-rod fingers. Fig. 10 represents a back view, and Fig. 11 a plan, of a portion of a lay, showing 55 a modification. Figs. 12 and 13 represent a back elevation and a plan of a further modification. Figs. 14 and 15 are similar views of a still further modification.

In carrying out our invention the vertical 60 picking-shafts A, picking-sticks B, lay-beam C, and other parts of the loom not particularly mentioned in the following description are of the ordinary construction and operated in the usual manner. A shuttle-box D is 65 formed at each end of the lay-beam C, as usual, and at the back of each shuttle-box D is a bar E, fulcrumed on a pin at E'. One side of the said bar projects a short distance into the interior of the shuttle-box D and 70 there forms a swell at E². The fulcrumed bar E may extend on the back of the lay-beam C and terminate with an arm at E³.

To the under side of the lay-beam C is mounted a shaft G, as usual, commonly called 75 a "stop-rod," and to this shaft are secured arms H, terminating vertically, one arm near to each end of the said shaft, and on the said shaft are formed stop-fingers J, as usual, which are held in the position shown by Figs. 80 2 and 5—that is, raised clear of the stop-blocks J'—by the contraction of the spiral spring K, held in tension between a hooked arm G', projecting from shaft G, and an extension G², secured to one of the oscillating 85 arms C', supporting the lay-beam C.

On the lay-beam C, moving toward the front of the loom in the direction of the arrow in Fig. 2 for beating up the weft, a short arm L, secured to and projecting from shaft G, 90 comes in contact with one end of a lever L', (shown by Figs. 3 and 4,) and unless the shaft G is held stationary in the manner as hereinafter described during the beat-up of the weft the action of the spiral spring S or flat 95 plate-spring S', applied in the manner shown, will cause the shaft G to slightly rotate in its journals and the stop-fingers J to descend from the position shown by Figs. 2 and 5 to that shown by Figs. 3 and 4, and thereby 100 stop the loom by the stop-fingers J coming in contact with the stop-blocks J'; but when

there is a shuttle in either shuttle-box the stop-fingers J are held clear of the stop-blocks J', as shown by Figs. 2 and 5, and the friction removed from the shuttle-box D in the 5 following manner.

Each shuttle-box D is provided with an ordinary picker, which slides on rod M and is operated in the usual manner, and when a shuttle is driven home into a shuttle-box D 10 at either end of the lay-beam C it is compressed between the swell E² on one side of the shuttle-box and the fixed flange D' on the opposite side of the shuttle-box, thus moving the bar E backward to the position 15 shown by dotted lines in Fig. 7, the arm E³, attached thereto, being also moved to the position shown by dotted lines, thus propping the arms H, and thereby retaining arms H and shaft G in a stationary position, so that 20 on the lay-beam C moving forward in the direction of arrow in Fig. 2 the short arm L on coming in contact with the lever L' cannot operate the lever and shaft G in the manner as hereinbefore described. Consequently the 25 said shaft and stop-fingers J are held in the position as shown by Figs. 2 and 5 by the end of arm E³ engaging with vertical arm H in a manner so as to act as a prop to the vertical arm H, and thereby prevent any movement 30 of the shaft G in the direction for the stop-fingers J to engage with the stop-blocks J', and by the arm E³ propping the vertical arm H in the manner described the pressure of the spiral spring S, Fig. 3, or flat plate-spring 35 S', Fig. 4, acting through the short arm L and vertical arm H against the end of arm E³, forces the fulcrumed bar E backward a distance that the swell E² is clear of the shuttle within the shuttle-box D, thereby removing 40 from the shuttle the friction hitherto binding it within the shuttle-box D, as is the case when the vertical arm H acts direct upon the fulcrumed bar E in the manner as hitherto. Thus by our combination and arrangement 45 of mechanism the power required to propel the shuttle across the loom from one shuttle-box to the other is considerably reduced, consequently reducing in a proportionate degree the wear and tear of the picking mechanism.

Fig. 9 is an end view of the stop-rod shaft with the hooked arm and a portion of the spiral spring on the same side of the stop-rod shaft as the stop-rod fingers. When the 55 hooked arm G' is on the same side of the stop-rod shaft G as the fingers J, the said fingers are held in the position shown by Figs. 2, 5, and 9 during some portion of the reciprocating movement of the lay-beam C by the small 60 pulley G² on end of lever G³, secured to stop-rod shaft G by passing over the upper surface of bracket G⁴, secured to some convenient part of the loom, such as to one of the end frames. The lay-beam C on moving in 65 the direction of arrows in Figs. 2 and 9 when near the termination of the forward motion for beating up the weft the before-mentioned

small pulley G² will leave the upper surface of bracket G⁴, and if the vertical arms H are not held back in the manner as before described the spiral spring K is at liberty to contract and bring the fingers J into the position shown by Figs. 2 and 4, and thereby stop the loom on coming in contact with the stop-blocks J'; but if the arms H are propped 75 or held back the stop-fingers J are held clear of the stop-blocks J', as shown by Figs. 3 and 5.

Fig. 10 represents a back view, and Fig. 11 a plan, of one end of the lay-beam C, showing a vertical arm H constructed in a modified manner, by which the upper portion of said arm at H' is pivoted at H² and held in the position shown by a spring S². The modified arm is attached to the shaft G and operated in the manner as before described; but should the shuttle be only partly driven into the shuttle-box D, so that the bar E is not moved back the required distance for the arm E³ to properly engage with and prop the said vertical arm, but only with the edge thereof, the upper portion of the arm at H' will yield in the direction of curved arrow, thus allowing the arm E³ to pass and not hold or prop back the arm H and the stop-fingers J to come 95 in contact with the stop-blocks J' and stop the loom in the manner as hereinbefore described; but should the arm E³ hold back or prop the vertical arm at H' then the stop-fingers J are held up clear of the stop-blocks 100 J' and the binding of the shuttle within the shuttle-box D removed.

Figs. 12 and 13 represent a back elevation and plan of one end of the lay-beam C. In this case instead of the fulcrumed bar E being continued and terminating with an arm E', as before described, we utilize a bar E of the ordinary description and apply a short lever N, fulcrumed on a pin E'. The application of this lever, as will be readily understood, is the same in effect as the mechanism before described. On the fulcrumed bar E being moved backward by the shuttle entering the shuttle-box D the short lever N is operated in the direction that one end of said lever is in the position for holding back or propping the vertical arm at H', and thereby removing the frictional binding of the shuttle within the shuttle-box D, also preventing the stop-fingers J coming in contact with the stop-blocks J'.

Figs. 14 and 15 are similar views to those last described, showing a back elevation and plan of one end of the lay-beam, and Fig. 15 is a side elevation of our modified arm. According to this arrangement we move the vertical arms H farther from the ends of the lay-beam C and mount a lever P on a stud supported by bracket P', secured to the lay-beam C. One end of this lever P engages with the back of fulcrumed bar E. The said lever has a projecting arm P², which, as will be readily understood, when the fulcrumed bar E is forced backward by the shuttle en-

tering into the shuttle-box D the end of lever P in contact with the fulcrumed bar E is also forced backward and the arm P² of lever P moved into position for engaging 5 with the upper portion H' of vertical arm H, and thus hold or prop the same in the manner as before described, so that the frictional binding of the shuttle within the shuttle-box is removed and the stop-fingers J prevented 10 from coming in contact with the stop-blocks J', and thereby stopping the loom.

What we claim as our invention is—

1. In combination, the swell arranged at the shuttle-box to be operated by the shuttle, a stop-block and stop-finger, means for operating the stop-finger, and a device interposed between the means for operating the stop-finger and the swell for controlling the action of said finger, said operating means 15 acting through said device to relieve the shut- 20

tle from the pressure of the swell, substantially as described.

2. In combination, the swell arranged at the shuttle-box, a stop-block, a stop-finger coöperating therewith, spring-pressed means 25 on the lay for operating the stop-finger, a device interposed between said spring-operating means and the swell whereby the position of the swell causes said device to control the action of the stop-finger, said spring-pressed 30 operating means acting through said device to relieve the shuttle from pressure of the swell, substantially as described.

In testimony whereof we have hereunto set our hands in the presence of two witnesses. 35
